CLAIM

The ornamental design for a finishing sander or similar
article, as shown.

DESCRIPTION

FIG. 1 is a left side elevational view of the finishing
sander or similar article showing my new design.

FIG. 2 is a right side elevational view thereof.

FIG. 3 is a front elevational view thereof.

FIG. 4 is a rear elevational view thereof.

FIG. 5 is a top plan view thereof.

FIG. 6 is a bottom plan view thereof.

The dust collection bag in FIGS. 1, 2 and 4-6 has been
shaded for fabrics which is continuous over the surface
of the bag. The handle in FIGS. 1-5 of the sander has
been shaded to represent a textured surface.

FIG. 1FIG. 2FIG. 4

FIG. 3

FIG. 5FIG. 6
